UNITED STATES PATENT OFFICE.

MAX TAIGMAN, OF NEW YORK, N. Y.

STARTING-BOX.

1,116,952.

Specification of Letters Patent. Patented Nov. 10, 1914.

Application filed May 8, 1914. Serial No. 837,198.

To all whom it may concern:

Be it known that I, MAX TAIGMAN, a citizen of the United States, and a resident of the city of New York, borough of Manhattan, in the county and State of New York, have invented a new and Improved Starting-Box, of which the following is a full, clear, and exact description.

Among the principal objects which the 10 present invention has in view are: to provide a box of the character indicated, wherein all electrical connections are protectively covered; to provide a resistance unit operably constructed independent of the containing box therefor; to provide a terminal panel arranged to receive the electrical supply circuit leads; and to simplify the construction and reduce the cost thereof.

Drawings.—Figure 1 is a front side view 20 of a starting box constructed and arranged in accordance with the present invention, the front cover thereof being removed to expose the interior of the box; Fig. 2 is a rear side view, the cover of the manhole being partly lifted to expose supply lead circuit terminals; Fig. 3 is a perspective view of a resistance unit constructed and arranged in accordance with the present invention, the view showing the front face of the unit; 30 Fig. 4 is a perspective view of the same, the view showing the rear face of the unit; Fig. 5 is a detail view, on an enlarged scale, taken as on the line 5—5 in Fig. 3. Fig. 6 is a front view of a modified form of a resistance 35 unit constructed and arranged in accordance with a modified form of the invention; Fig. 7 is a rear view of the same.

Description.—When constructed in accordance with the present invention, the 40 box 10 supports what may be termed a local circuit, in that the terminal contact 11 and the spring wiper 12 are supported on the frame of said box, being insulated therefrom by a pad 13, as shown best in Fig. 1 of the drawings. The box 10 supports a starting lever 14, providing as a pivot therefor a post 15 to receive the hub 16 of said lever. Insulated from the body of the lever 14 and supported by the metal plate 17 of said lever 45 50 is a suitable contact member, against which the wiper 12 constantly bears, and through which the operating electric current is conveyed, by way of the plate 17, and the extensions 18, to a brush 19 and to buttons 20,

21 and 22. The brush 19 is yieldingly 55 pressed on the surface of said buttons by a spring 23.

The construction and arrangement of the parts just mentioned is more fully disclosed in an application for Letters Patent of the 60 United States, for improvements in starting boxes, filed by me April 9, 1914, and bearing Serial No. 830,675, to which application cross reference is here made.

By reference to the application mentioned, 65 it will be seen that the lever 14 and parts connected therewith constitute a single element or unit in a starting box constructed and arranged in accordance with the present invention, the assemblage of said lever and box 70 being made when said lever and parts are dissociated from the box and resistance unit. With this in view, it will also be noted that the completed starting box as herein shown is constituted by three elements or units, to 75 wit, the lever 14, the box 10, and the resistance unit in which is incorporated the buttons 20, 21 and 22. In the resistance unit, as best seen in Figs. 3 and 4 of the drawings, the panel 24 is supported between metal 80 framing members 25 and 28, and between the lugs 26 and 27 thereof. At the end of the framing member 25, a circular flange 29 is formed, said flange being furnished with an inset pocket 30 to hold a nut 31, which, when 85 manipulated on a bolt 32, sets the flange 29 tight against one end of a resistance coil spool 33. The opposite end of the spool 33 is held by a standing cheek-piece 34, with which the member 28 is provided. The 90 cheek-piece 34 is provided with a recess similar to the pocket 30 to hold a nut similar to that shown in the drawings and designated by the numeral 31. The cheek-piece 34 is upraised above the spool 33, and is provided 95 at the upper edge with an offset 35. As best seen in Fig. 5 of the drawings, the offset 35 has formed therein a pocket 36 provided to receive the head 37 of a binding screw 38.

Preferably the spool 33 and the panel 24 100 are produced separately and from porcelain or other molded material, wherein the various holes to receive screws 39, 40 and 41 may be formed. The screws 41 are passed through elongated holes 42, shown best in 105 Fig. 4 of the drawings, said holes being elongated to correspond with open-ended slots 43 formed in the lugs 27. The slots 43 and

holes 42 being thus formed and alined, there is provided a certain latitude of adjustment necessary for the fitting of the framing members and panels connected therewith, to the box 10. As disclosed in the application above referred to, the box 10 is provided with brackets having tapped perforations to receive set screws 41.

The offset 35 is provided at its outer edge with an overhanging wall 44, the office of which is to maintain the service disposition of the bracket terminal 45. The terminal 45 is held firmly to the offset 35 by the screw 38 and nut 46. To insulate said bracket from its offset, a packing 47 is placed between the surfaces of the bracket and offset. The screw 38 is insulated from the offset 35 by the bushings formed of insulating material, as shown best in Fig. 5 of the drawings. The purpose of the insulated construction is to prevent the electric current introduced by the jumper wire 48 to said bracket from passing to the cheek-piece 34 and from thence to the box 10.

The screws 40 are employed to hold binding posts 49, 50 and 51, which binding posts, as shown best in Figs. 2 and 4 of the drawings, extend from the back of the panel 24. To the first-mentioned post, the main supply wire 52 is operatively connected. To the last-mentioned post, the opposite main wire 53 is operatively connected, and to the intermediate post 50, a shunt wire 54 is operatively connected. It will be understood that the shunt wire is only used where the installation is such as to require its employment. The wires 52, 53 and 54 are bound together to form a cable 55, which extends through a gasket 56 of suitable insulating material in the side of the box 57 formed on the back cover 58 of the box 10. Preferably, the box 57 has elevated or raised walls to permit the formation therein of the orifice in which the gasket 56 is placed. The box 57 is normally closed by a drop cover 59, which cover is mounted on a pivot pin 60 to fall into position against the standing edge 61 with which the box is provided.

From the foregoing it will be seen that when the resistance unit is installed in the box 10, the wires 52, 53 and 54 may be connected in service with the binding posts 49, 51 and 50, respectively. Also, it will be seen that when the cover 59 is permitted to drop, the box 57 is closed, and danger arising from contact of the personal clothes of the operator with the posts 49, 50 and 51 is avoided.

From the foregoing it will be seen that the resistance unit may be fully connected with the electric source prior to installing it in the box 10, if such be desired, or may be installed as a unit, and the wires 52, 53 and 54 be thereafter operatively connected with the unit. In any case, the current entering

by the wire 52 is transferred from the post 49 via the wire 48 to the bracket terminal 45. From the terminal 45, the current is transferred to the contact 11 through any suitable means structurally connected with the front cover of the box 10, as fully disclosed in the application above referred to. From the contact 11, the current is transferred to the spring wiper 12, and from thence to the plate 17, extension 18 and brush 19 of the lever 14. Normally, the brush 19 rests upon one or other of the buttons 20, which are normally disconnected from the resistance coil on the spool 33. The button 21 is connected by means of a jumper strap, with a contact band 63. The shunt wire 54 is also connected with this button by the short extension 64 of the jumper strap 62. The succeeding buttons 22 are each connected by straps 65, 66, and 67, respectively, with the resistance coil on the spool 33, and the latter strap, by means of its extension 67, is directly connected with the binding post 51 and wire 53, so that when the brush 19 rests upon the button 22 corresponding therewith, the coil on the spool 33 is cut out.

While I have herein described the resistance unit as having the panel 24 and the spool 33 connected by metal framing members, it will be understood that I may substitute for said spool, a spool or form integrally formed with or rigidly connected to the panel 24, upon which extension or spool a resistance coil may be wound, but in every event, it will be seen, the resistance unit referred to has incorporated therewith the binding posts for the current supply, and is totally concealed within and thoroughly insulated from the box 10.

It will be seen that when employing a structure such as herein disclosed, by the removal of the cotter pin 68 the elements may be separately removed from the box 10 in the manner as follows, to wit: The lever 14 and parts connected therewith may be lifted from the post 15, becoming automatically disengaged from the wiper 12. By manipulating the screws 41, the resistance unit may be lifted forward out of the box 10, the cable 55 being drawn through the gasket 56. The unit in this position may be repaired or replaced, or disconnected from the current supply wires and removed or replaced. Without removing the lever 14 and parts connected therewith, the operator may at any time, by lifting the cover 59, expose for purpose of alteration or repair, the binding posts 49, 50 and 51, the screws whereof may be tightened or the terminals thereof brightened.

In the modified form of the invention shown in Figs. 6 and 7, there is substituted for the framing members 25 and 28 of the preferred form, framing members 69 and 70. The framing members 69 and 70 have raised

portions 71 similar to the portion 34 shown in the drawings illustrating the preferred form, and offsets 72, which resemble the offsets 35 in the preferred form. The offsets 72 are extended from both framing members 69 and 70, and are both provided with bracket terminals 45, said terminals being disposed in line. The offset 72 and bracket terminal 45 mounted on the framing member 69 are in the modified form the substitutes for the terminal contact 11 of the preferred form. In the modified form, the spring wiper 12 is incorporated in the unit structure, and is supported fixedly by a screw 73 on a rectangular bracket 74, which bracket is integrally formed with the framing member 69. The opposite end of the wiper 12 rests upon a pad 75, which pad is fixedly mounted on a rectangular bracket 76. The brackets 74 and 76 are to all intents and purposes duplicates or correspondences, being approximately the same shape, and having approximately the same extension. The wiper 12 is insulated from the bracket 74 by a pad 77. In this form of the invention, the wiper 12 is electrically connected with the bracket 45 mounted on the framing member 69 by means of a jumper wire 78. As above explained, the cover for the box 10 is provided with a connecting spring bridge or jumper to electrically connect the terminals 11 and 45 in the preferred form, and the same jumper performs the same function for the two terminals 45, 45 in the modified form. In the modified form, it will be observed that the box 10 forms no part of the electric circuit or of the support for members incorporating the circuit, other than the resistance unit. It will also be observed that the resistance unit is fully assembled ready for installation in the box prior to being placed therein. Further, in this form provision is made so that the connection of the installation to the main or electric supply cable 79 is effected by inserting the split pins 80 in a Menchen plug 81. Sockets are formed in the plug 81 to receive metal tubes 82. Through threaded perforations 83, binding screws 84, 85 are extended. Under the heads of the screws 84, 85 are secured a jumper strap 86 and the wire 48, respectively. The pins 80 of the panel 24, when forced within the tubes 82, electrically connect the unit and the lever 14 with the electric source or supply. To accommodate the sockets provided to receive the pins 80, the panel 24 has an extension 87. The extension 87 is normally protected by the side walls of a pocket 88, into which the plug 81 extends when the pins 80 are forced into the tubes 82, the joint between the plug 81 and the extension 87 being covered and protected by the sides of the pocket 88.

From the foregoing, it will be seen that when employing a unit constructed and ar-

ranged in accordance with the modified form of the invention shown in Figs. 6 and 7, the box 10 becomes in substance a supporting member only, and is not essential to the operation of the device except in so far as it covers the resistance unit and pivotally supports the lever 14. In other words, by this construction the installation of a mechanism requires merely the handling of two members, to wit, the resistance unit and the starting lever 14.

Claims:

1. A starting box having a starting unit, comprising a hollow spool for receiving a resistance coil; a plurality of terminal buttons electrically connected with different sections of said coil; a plurality of binding posts adapted to receive the terminals of circuit supply mains; a molded panel having formed therein and coeval therewith perforations for holding said buttons and said posts; metal frame members for supporting in operative relation said panel and said spool; and means, embodying a bolt and screw nuts therefor, disposed within said spool for holding said frame members in position.

2. A starting box having a starting unit, comprising a hollow spool for receiving a resistance coil; a plurality of terminal buttons electrically connected with different sections of said coil; a plurality of binding posts adapted to receive the terminals of circuit supply mains; a molded panel having formed therein and coeval therewith perforations for holding said buttons and said posts; metal frame members for supporting in operative relation said panel and said spool; means, embodying a bolt and screw nuts therefor, disposed within said spool for holding said frame members in position; and a terminal member mounted on one of said frame members and extending therefrom, said terminal members being electrically connected with one of said binding posts.

3. A starting box having a starting unit, comprising a hollow spool for receiving a resistance coil; a plurality of terminal buttons electrically connected with different sections of said coil; a plurality of binding posts adapted to receive the terminals of circuit supply mains; a molded panel having formed therein and coeval therewith perforations for holding said buttons and said posts; metal frame members for supporting in operative relation said panel and said spool; means, embodying a bolt and screw nuts therefor, disposed within said spool for holding said frame members in position; a terminal member mounted on one of said frame members and extending therefrom, said terminal members being electrically connected with one of said binding posts; and a containing box for said

- unit, having a terminal member disposed in correspondence with, and removed from said first-mentioned terminal member.
4. A starting box having a starting unit, comprising a hollow spool for receiving a resistance coil; a plurality of terminal buttons electrically connected with different sections of said coil; a plurality of binding posts adapted to receive the terminals of circuit supply mains; a molded panel having formed therein and coeval therewith perforations for holding said buttons and said posts; metal frame members for supporting in operative relation said panel and said spool; means, embodying a bolt and screw nuts therefor, disposed within said spool for holding said frame members in position; a terminal member mounted on one of said frame members and extending therefrom, said terminal members being electrically connected with one of said binding posts; a containing box for said unit, having a terminal member disposed in correspondence with and removed from said first-mentioned terminal member; and a switch arm pivotally mounted on said box, said arm being continuously connected with said first-mentioned terminal member and movable to be temporarily connected with said buttons.
5. A starting box, comprising a switch panel formed of insulating material; a plurality of terminal buttons; a resistance coil having sections thereof operatively connected with said buttons; and a plurality of current service binding posts permanently mounted in said panel to receive a socketed plug connector, embodied in an electric service supply; and a containing box for said panel having a pocketed opening protecting said binding posts and for receiving said connector.
6. A starting box, comprising a switch panel formed of insulating material; a plurality of terminal buttons; a resistance coil having sections thereof operatively connected with said buttons; a plurality of current service binding posts permanently mounted in said panel to receive a socketed plug connector, embodied in an electric service supply; and a containing box for said panel having a pocketed opening protecting said binding posts and for receiving said connector.
7. A starting box, comprising a switch panel formed of insulating material; a plurality of terminal buttons; a resistance coil having sections thereof operatively connected with said buttons; a plurality of current service binding posts permanently mounted in said panel to receive a socketed plug connector, embodied in an electric service supply; an extension of said panel for mounting said posts; and a containing box for said panel having an open pocket to hold said extension and connector, the outer edge of said pocket extending beyond the meeting wall of said extension and said connector.

In testimony whereof I have signed my name to this specification in the presence of two subscribing witnesses.

MAX TAIGMAN.
